METHOD AND APPARATUS FOR ROLLING

Adam J. Hazlett, Baltimore, Md., assignor to The
Eastern Rolling Mill Company, Baltimore, Md.,
a corporation

Application October 20, 1934, Serial No. 749,243

9 Claims. (Cl. 29—17)

My invention relates to the art of rolling and, in particular, to the manufacture of so-called "full finished" steel sheets in packs.

Users of full finished sheets, such as automobile body and metal furniture makers, demand a very high quality of product, particularly as to surface condition. Even the minutest indentation or imperfection in the surface of a sheet will cause it to be rejected, because such imperfections cannot be easily concealed, even though the fabricated article is to be painted or lacquered.

Full finished sheets are now usually made by rolling breakdowns in packs. Great care is taken to prevent the sheets from adhering to each other. The preferred, loose condition of the breakdowns preserves the essential smoothness of the surface of the finished sheet but contributes to the occurrence of defects known to the trade as "pinchers", "squeezers", "spreaders", and "flopplers". These defects appear to result from the movement of a portion of the whole pack or of one or more breakdowns relative to the remainder of the pack. Such defects are very serious because they not only cause the rejection of the individual sheet in which they occur, but also because they are apt to cause denting or marking of the other sheets in the same pack.

The rolls of the usual two-high hand mill are operated hot and, since they are turned in the lathe while cold, they are turned concave so that when heated up to the normal operating temperature, they will conform to true cylindrical shape as nearly as possible. As a practical matter, it is substantially impossible to maintain the shape of the rolls perfectly cylindrical for any length of time because of rolling interruptions, variable bearing friction factors, and different widths of product. The resulting irregularities in the roll contour aggravate the problem of producing a high percentage of prime sheets because the irregularities in the roll contour resulting from the changing temperature of the rolls are the immediate cause of the defects above mentioned, viz., pinchers, squeezers, spreaders and flopplers.

The net result of the conditions outlined above is that the percentage of prime sheets turned out by hot pack rolling is very low, in some cases as low as 65% of the charged pieces. It is usual for producers of high-grade sheets to start the manufacturing process with about a 20% excess of pieces to make up for the losses inevitably encountered. Even so, it is frequently necessary to resort to a second rolling before sufficient prime sheets can be obtained to complete an order. The problem of producing a high percentage of prime sheets is particularly troublesome when sheets over 60" wide and/or over 96" long are being rolled.

I have invented a method and apparatus for

rolling sheets in packs which eliminates the above mentioned defects and makes it possible to roll a higher percentage of prime sheets than has ever been obtained heretofore. The invention is very simple, yet highly effective, and does not involve any material increase in the amount of equipment or the processing steps usually employed in conventional practice. In accordance with my invention, I start the leading end of a pack into the roll pass and then subject the remainder of the pack to a progressive, preliminary, rolling or flattening operation under pressures much lower than those encountered in the mill itself. This permits irregularities in the various sheets of the pack to be ironed out before the pack is gripped so tightly between the mill rolls as to make any further individual adjustment of the sheets impossible. The apparatus which I use to carry out the method is simply a so-called "billy roll" arrangement by which the portion of the pack approaching the mill pass is compressed against the surface of one of the mill rolls to flatten the pack initially before entering the mill. When entering the pack into the mill, the billy roll is moved out of the pass line so that it does not interfere in any way with the normal operation.

For a complete understanding of the invention, reference is made to the accompanying drawings, illustrating a present preferred embodiment of apparatus useful for performing the method. In the drawings:

Figure 1 is a partial end elevation of a sheet mill having the invention applied thereto;

Figure 2 is a partial side elevation of the mill;

Figure 3 is a plan view of the billy roll arrangement;

Figure 4 is a side elevation thereof;

Figure 5 is an end elevation thereof; and

Figure 6 is a partial sectional view along the line VI—VI of Figure 3.

Referring now in detail to the drawings and, for the present, to Figures 1 and 2, a rolling mill 10 comprises housings 11 having windows 12 therein and rolls 13 and 14 having their necks 15 journaled in bearings 16 disposed in the windows. The construction of sheet mill shown is conventional and, therefore, need not be described further.

In order to carry out my invention, I provide trunnions 17 projecting inwardly from the roll housings on the entering side of the mill. The trunnions have a common axis parallel to the axes of the rolls and provide a pivotal mounting for a tilting billy roll frame 18 having side plates 19 and a transom 20 extending transversely therebetween.

A pressure roll 21 and a guide roll 22 are journaled on shafts 23 extending transversely of the frame 18, on bearings 24. A clevis 25 is formed

at each end of the transom 20. A piston rod 26 reciprocating in a pneumatic cylinder 27 is connected to each clevis 25. The cylinders 27 are pivotally suspended from brackets 28 extending outwardly from the mill housings 11. The cylinders 27 are double acting and are controlled by a feed valve 29 through a simple system of piping indicated generally at 30.

The side plates 19 are provided with lubricant tubes 31 extending to points adjacent the bearings 24. One side plate, specifically the one shown at the left in Figures 2 and 5, is provided with a nozzle pipe 32 having a plurality of openings therein. A steam supply pipe 33 lies in a groove formed in the inner face of the side plate, as shown in Figure 6, and, through a flexible connection, connects the nozzle pipe to a source of steam. The jets emitted by the nozzle pipe constitute an effective means for blowing scale off the pack before it enters the mill.

Having explained the construction of the apparatus, I shall now briefly outline the operation thereof whereby the method of my invention is performed.

The tilting billy roll arrangement is normally maintained in the position shown in solid lines in Figure 1. In this position, the pressure roll 21 is substantially tangent to the pass line indicated at 34 and permits the introduction of a pack to the mill in the usual manner. As soon as the pack has entered the roll pass, the roller operates the valve 29 to cause the cylinders 27 to tilt the frame 18 to the dotted line position shown in Figure 1. The pack immediately assumes the position indicated by dotted lines in Figure 1 and is progressively flattened between the pressure roll 21 and the upper roll 13 of the mill 10. The pressure exerted on the material by the roll 21 is obviously not as great as that to which the material is subject in the mill itself. It is sufficient, however, to flatten the sheets of the pack transversely in a progressive manner before the advancing portions of the pack have been gripped between the mill rolls after which further lateral adjustment of the individual sheets is impossible. In addition to stretching the sheets crosswise against the top roll and ironing out the irregularities in the pack before it enters the bite of the rolls, the pressure roll holds the pack firmly against the work roll so that no slippage between the mill rolls and the pack occurs. The guide roll 22 holds down the trailing end of the pack and prevents fluttering thereof.

I have found the billy roll arrangement described herein a very effective means of reducing the occurrence of the defects usually observed in hot rolled sheets. The pressure roll 21 appears to exert a very effective smoothing or ironing action on the sheets while they are still fairly loose in the pack, and removes any fullness which might, in elongation, wrinkle the sheets and cause pinchers, squeezers, etc. The invention makes possible a marked increase in the percentage of prime sheets produced on a given mill, with a consequent reduction in the cost thereof. Imperfect sheets, of course, have rather small salvage value and must be charged against the cost of the primes actually turned out. The invention does not disturb any of the advantages of the ordinary system of pack rolling but actually increases the utility thereof. The speed of operation need not be affected by the invention and the cost of the necessary equipment is quite small.

Although I have illustrated and described herein but one preferred embodiment of apparatus

and practice of the method of my invention, it will be apparent that many changes therein may be made without departing from the spirit of the invention or the scope of the appended claims.

I claim:

1. In a rolling mill, spaced housings with reducing rolls journaled therein, a frame tiltably mounted between said housings, a pressure roll journaled in said frame for cooperation with one of said mill rolls to cause material entering the mill to depart from the common tangent to the mill rolls, a nozzle tube carried by said frame, and means including said tube for discharging fluid or vapor jets directed on to the material.

2. In a method of rolling sheets, the steps including entering a pack of sheets between reducing rolls, substantially along the line of the common tangent thereto, deflecting successive portions of the pack away from said line, and maintaining them in contact with one of said rolls as they enter the pass between the rolls.

3. The method defined by claim 2 characterized by the additional step of progressively holding down portions of the pack rearwardly of the portion deflected into engagement with one of said rolls.

4. In a method of making sheets, the steps including heating a pack of breakdowns, entering the leading end of the pack between reducing rolls substantially along the plane tangent to both rolls, and deflecting the remaining portions of the pack into engagement with one of said rolls prior to its being engaged by both the rolls.

5. In a method of making sheets, the steps including entering a pack of sheets between reducing rolls substantially along the plane tangent to both rolls, progressively pressing the pack across its width between one of said rolls and another roll, and maintaining subsequent portions of the pack in contact with said one of said first mentioned rolls as it enters the pass between the rolls.

6. In a method of making sheets, the steps including entering a pack of sheets between reducing rolls substantially along the plane tangent thereto in common, and subjecting the portions of the pack progressively to a preliminary rolling between one of said rolls and another roll before they pass between the rolls first mentioned.

7. In a method of making sheets, the steps including entering a pack between reducing rolls substantially along the plane tangent thereto in common, and progressively flattening successive portions of the pack by passing them between one of said rolls and another roll as they approach the first mentioned rolls.

8. In a method of making sheets, the steps including entering a pack between reducing rolls substantially along the plane tangent thereto in common, and subjecting the remaining portions of the pack progressively to a preliminary ironing out between one of said rolls and another roll.

9. In a method of making full finished sheets, the steps including forming a pack of sheets, heating them to rolling temperature, entering the leading end of the pack between reducing rolls substantially along the plane tangent to both rolls, and causing the subsequent portions of the pack to depart from said common tangent to the rolls and pass between one of said rolls and another roll before entering therebetween, under sufficient pressure to prevent lateral creeping of the pack.

ADAM J. HAZLETT. 75
